INDUSTRIAL GAUGING HEAD FOR DETECTING MATERIAL PROPERTIES

John Paul Kennedy, Columbus, Ohio, assignor to Industrial Nucleonics Corporation, a corporation of Ohio

Application May 15, 1957, Serial No. 46,183

Term of patent 14 years

(Cl. D52—1)

Fig. 1

Fig. 2

Fig. 1 is a perspective view of an industrial gauging head for detecting material properties showing my new design; and

Fig. 2 is another perspective view taken from a different angle.

The undisclosed end of the industrial gauging head is substantially plain in appearance.

I claim:

The ornamental design for an industrial gauging head for detecting material properties, as shown and described.
